TRAFFIC CONTROL SYSTEM

Charles D. Geer, New Haven, Conn., assignor to
 The Engineering and Research Corporation,
 New Haven, Conn., a corporation of Con-
 necticut

Application November 1, 1930, Serial No. 492,731

7 Claims. (Cl. 177—337)

This invention relates to a functionally and structurally improved traffic control system and apparatus forming such system.

It is an object of the invention to provide a system and apparatus of the nature stated capable of use in numerous different associations but primarily intended to be employed at the point of intersection of two vehicle lanes and specifically vehicle lanes of the automobile type. Where so employed, the present apparatus will provide a system functioning in response to the flow and condition of traffic and which system will operate in an improved manner to prevent accidents at the point of intersection and will 15 additionally expedite to a maximum extent the traffic flow.

A further object of the invention is that of furnishing an apparatus for controlling the flow of traffic in such manner that a vehicle or vehicles traversing one lane will have ample opportunity to negotiate the intersection before right of way is transferred to the other vehicle lane.

Another object is that of furnishing an apparatus of this character, the parts of which will be relatively few in number and individually simple and rugged in construction, these parts functioning over long periods of time with freedom from mechanical and electrical difficulties.

With these and other objects in mind, reference is had to the attached sheet of drawings illustrating one practical embodiment of the invention, and in which:

Fig. 1 shows diagrammatically the intersection of two vehicle lanes and moreover illustrates an apparatus embodying the present invention and in association with such lanes; and

Fig. 2 is a similar view of a detailed layout of apparatus suitable to achieve the results to be accomplished by the present invention.

For the sake of simplicity of illustration, the present invention has been shown as embodied in a traffic control system installed at the point of intersection of a cross street and main highway. In the drawing, the latter is indicated at A and the cross street is designated B. As hereinafter described and in line with this example, vehicle actuated controls are shown only in the cross street. However, under actual installation conditions, these controls will usually although not necessarily be in both streets or in any fur-

ther number of streets which may exist at the point of intersection.

Thus as illustrated, a signal 5 is disposed conveniently adjacent the point of intersection of the two lanes and has signal lights visible to vehicles moving along such lanes and approaching the intersection. These lights have been indicated at 6 to 9 inclusive in Fig. 2 and embrace preferably two green lights and two red lights, the former indicating right of way and the latter 10 signalling a halt to the vehicles. To this end, these lights are preferably colored green and red respectively which coloration may be achieved by the use of colored bulbs and/or lenses or in any other suitable manner. Moreover, if the present invention is embraced in a system of the nature afore referred to, the vehicle actuated or responsive controls 10 or 11 are disposed in only the cross street. While the signalling means 20 may be of any desired character and the vehicle actuated controls may also embrace any mechanism suitable to operate in response to the passage of a vehicle along the vehicle lane, it is preferred that such controls be in the nature of pressure operated switches which incident to the 25 passage of a vehicle function in order to close a circuit. It will be observed that a plurality of these switches are, in the present exemplification, associated with the cross street. These switches are connected in parallel and arranged two to 30 each side of the intersection. Accordingly, actuation of one of these controls will close the circuit common to all of them. For the sake of simplicity only two controls have been shown in Fig. 2 and indicated by the reference numeral 11. 35

The functionings of the signalling means 5 in response to actuations of the controls 10 and 11 are governed by a timer or control mechanism 12, the detailed construction of which has been shown in Fig. 2. In this view and as afore 40 brought out, the several vehicle actuated controls 10 are shown in the form of parallel switches 11. A closing of either switch permits current to flow from lead 13 through quick acting relay 14 and thus to lead 15. The leads 13 and 15 are connected 45 to a source of power supply (not shown) and the armature of the relay 14 serves to move a switch 16 from engagement with the contact arranged at the end of lead 17 into engagement with the contact at the end of lead 18. The parts as 50

shown in Fig. 2 are in a normal position, but an energization of the relay will as afore stated move the switch 18 which will permit current to flow from lead 13 through lead 18, thence through relay 18 and so through lead 20 to lead 15. This will serve to operate and lock in relay 19 by virtue of the fact that the armatures controlled thereby will shift the switches 21 and 22 into engagement with contacts forming parts of leads 23 and 24 respectively. Thus even though the switch 18 move rapidly out of engagement with the contact of lead 18, current will now flow through lead 28, a switch 26 interposed therein, lead 23, switch 21, relay 19 and so through lead 15 to lead 18. As afore brought out, the switch 22 moves into engagement with a contact associated with the lead 24 and current will now flow through this lead and relay 21, lead 28 and switch 28 from lead 13. Consequently, switches 30 and 31 will move to closed positions, thus through the former permitting current to flow through lead 32 and relay 33 interposed therein, through this switch, lead 24, switch 22 and so to lead 15. With the closing of switch 31, current may flow through lead 34, switch 35 interposed therein, and thence through switch 31 and so to lead 15.

Relays 14, 19, 27 and 33 are of the substantially instantaneous types. The switches 28, 35 and 29 are controlled by time delayed relays 36, 37 and 38 which may conveniently be of the oil dash pot type. In the embodiment under consideration, the first of these latter relays is set to open after five seconds, the second relay is set to open after thirty seconds and the third relay is set to close thirty seconds after having been continuously energized. All three relays return to their deenergized position substantially instantly. However, this time factor may be varied largely according to the conditions of installation which are met with.

Finally, it will be observed that the lead 13 may also supply current through the lead 39 to the signalling means or lights 8 and 9 interposed therein, and thence through switch 40 to the lead 15. This switch is controlled by relay 33 as is also a switch 41 interposed in a lead 42 within which there is additionally interposed the relay 38. Finally, it will be observed that the relay 33 shifts the switch 40 to a point at which it engages the contact associated with lead 43 within which are interposed the signalling means or lights 8 and 7 which latter when energized served to signal "Stop" to the highway and to accord right of way to the cross street.

With a set up of the parts such as that here-with illustrated, it will be obvious as afore brought out that an energization of the relay 14 follows each closing of the switch 11. Also as afore brought out, this results in a locking in of the relay 19 in turn energizing relay 27 to permit current to flow through lead 32 and relay 33 from lead 13 to lead 15. Consequently, an immediate shifting of the switches 40 and 41 follows and right of way is transferred from the highway to the cross street by virtue of the extinguishing of lights 8 and 9 and the energizing of lights 6 and 7. The energizing of the relay 33 will also cause circuit through relay 38 to be broken and the switch 29 will consequently move out of engagement with the contact at the end of the lead 28.

All of this will occur under usual conditions of operation upon a vehicle approaching over cross street B and operating the first vehicle actuated control of the pair. Under the setting of the parts and with relays 19 and 27 energized, relay

36 will be potentialized to operate in five seconds. However, due to the fact that the vehicle still has to negotiate and operate the second control, it will be obvious that this relay will be reset substantially instantly before the vehicle reaches the point of intersection. In other words, due to the closing of the second switch 11, the relay 14 will again be energized to shift the switch 18 and thus break the circuit through relay 38, the latter accordingly being reset to require the full 10 time interval before it operates. Upon the expiration of such time interval, the switch 26 is open and current will accordingly no longer flow through lead 28 thus causing a deenergization of relay 19 and permitting the switches 21 and 22 of the latter to open. Consequently, relay 27 will also be deenergized and as a result, relay 33 will be deenergized so that switches 40 and 41 will move back to the positions illustrated in which first current is being supplied to relay 38 and secondly the right of way is transferred from the cross street in favor of the highway due to the extinguishing of signals 6 and 7 and the reactivation of signals 8 and 9.

If thereupon a further vehicle approaches over lane B and operates the vehicle actuated controls resulting in a closing of the switch 11, relay 14 will function to again operate switch 18 and thus lock in relay 19 in the manner afore described. However, due to the fact that relay 38 requires—in the example given—thirty seconds to shift its armature so that the circuit through wire 28 is closed the switch 29 will be open and consequently the relay 27 can not be energized. Accordingly, no change in condition results despite the presence of a vehicle and the latter must wait a full thirty second period before transfer of right of way occurs. At the end of this period, relay 38 shifts switch 29 to closed position and thereupon the relay 27 functions to operate relay 33 so as to transfer right of way in the manner afore described and the cycle of operations is again repeated.

However, it will be recalled that the vehicle has come to a standstill after operating the first vehicle actuated control. Ordinarily the vehicle could gather sufficient momentum to negotiate the intersection five seconds after the transfer of right of way, but, while this vehicle would be able to get clear of the intersection before the right of way was retransferred, it will be obvious that in the case of a second, third and possibly more vehicles having passed the distant vehicle actuated control and awaiting such right of way, the delay factor of getting these vehicles under way after transfer of right of way would be such that they could not conceivably negotiate the intersection within the time interval allowed without the provision of the second vehicle actuated control. Accordingly, immediately in advance of the intersection, the second vehicle actuated control is arranged and therefore the second, third and other vehicles awaiting right of way will operate such control, causing a five second delay interval in the retransfer of right of way. Thus, all the vehicles will have ample time to negotiate the intersection, it being understood that each time the relay 14 operates, the relay 36 will be reset.

It would appear that the second vehicle actuated control might perform all necessary functions and that the distant control might be dispensed with. Such is not the case. A vehicle should register its presence sufficiently in advance of arriving at the intersection so that if it

receives right of way immediately it can avail itself thereof before deceleration is necessary. On the other hand, if the vehicle will have to await right of way, it should have registered its presence before deceleration begins, so that ample space is available for stopping.

Occasionally, a very heavy flow of traffic may occur on the cross street and this might prevent the highway from receiving right of way for a long period of time. However, due to the provision of relay 37, it will be obvious that right of way may not be retained in favor of the cross street for an indefinite period. As illustrated and described, this relay will function after thirty seconds to open the switch 35. This will cause the circuit through relay 21 to be interrupted, thus returning the signal to normal condition and closing the circuit through relay 38. Consequently, the parts will return to their normal condition except that relay 19 will remain locked in and, as a result, right of way which has been transferred in favor of the highway will be retransferred back to the cross street after thirty seconds.

It will be understood that, the innermost vehicle actuated controls, i. e. those controls which are nearest to the intersection, might be disposed at points relatively remote therefrom. For example, these controls might be anywhere from 25 to 100 feet from the intersection while the outermost controls might be as much as 200 to 300 feet away. This will be particularly true where the present invention is incorporated in a layout of apparatus to be installed at cross streets where high traffic speeds may occasionally be encountered. It will be obvious that in addition to the vehicle actuated controls illustrated—and as afore brought out—that the vehicle actuated controls will exist in the second lane. Where the innermost controls are substantially immediately adjacent the intersection, the advantages of the reset period and the manner in which the apparatus will function in the case of a number of vehicles awaiting right of way will be obvious. Where the innermost controls are somewhat spaced from the point of intersection, it will be apparent that at best only a few vehicles awaiting right of way will move beyond the innermost controls and these vehicles will have opportunity to negotiate the intersection during the minimum period granted when right of way is given. If further vehicles are awaiting the right of way beyond the innermost controls they accordingly in traversing such controls will reset the apparatus to extend the minimum period.

Summarized, it will be apparent that with the parts in the position illustrated in Fig. 2, a vehicle approaching over the cross street will cause—incident to an operation of the first vehicle actuated control—a substantially immediate transfer of right of way in favor of the cross street. If further vehicles are following the first named vehicle or are approaching over the cross street in the opposite direction and within a sufficiently close time interval, these other vehicles—incident to operation of the controls—will prolong the right of way for a period of time adequate to permit their crossing the intersection. In this manner, the cross street right of way may be maintained according to the present setting of the parts up to a period of thirty seconds. At this time, regardless of whether further vehicles on the cross street wish the right of way, the right of way will be transferred to the highway. However, if such right of way is desired at that

time, the system will "remember" the presence of such vehicles incident to the locking-in of the relay 19 or a functionally equivalent structure so that at the end of the highway right of way period, a retransfer of right of way to the cross street will occur. The same result will be true in the case of vehicles arriving during the highway right of way period.

By virtue of providing a multiplicity of vehicle actuated controls, the following salient advantages among others are derived: first, in the case of a vehicle moving over the cross street toward the intersection, the right of way given to the cross street will be retained for a period proportional to the speed of the vehicle. In other words, the spacing of the vehicle actuated controls their distance from the point of intersection, etc., may be so proportioned that one may safely say that no vehicle will require less than slightly in excess of five seconds to negotiate the intersection after having operated the first vehicle actuated control. Consequently, such vehicle will operate the first control and while it continues to move over the cross street, right of way will be transferred for a five second period incident to the setting of the relay 36. This relay however will be reset by the same vehicle incident to operation of the second control and this resetting will be for a like period. Now, assuming as afore brought out, that the vehicle is moving at high speed, we may arbitrarily say, for the sake of example, that only one second will be required for it to negotiate the distance between the first and second control. The second control resets the right of way period for an additional five seconds. Consequently, the entire right of way period in favor of the cross street will be six seconds. In the case of a slow moving vehicle, four seconds may be required between operation of the first control and the second control, making a total of nine seconds.

Second, in the case of a vehicle arriving just at the time that right of way is transferred back to the highway, or during the right of way period of the highway, no transfer of right of way to the cross street will result despite the operation of the vehicle actuated control. However, as afore brought out, the system will remember this. After the expiration of the highway right of way period, the system will accordingly transfer right of way back to the cross street. It will be remembered that the vehicle is at a standstill, and would have five seconds to negotiate the intersection. This would be sufficient for one or possibly two vehicles, but if further vehicles arrived during the highway right of way period and were awaiting right of way, five seconds would not be sufficient time for them to negotiate the intersection. However, by virtue of providing the second control, five seconds—in the example given—is allowed from the time this control is operated until right of way retransfers. Accordingly, ample opportunity will exist for all additional waiting vehicles to operate this second control and to negotiate the intersection up to the maximum right of way period for which the relay 37 or its equivalent structure is set.

Under varying conditions, the spacing of the vehicle actuated controls would be changed in many respects and the proximity of these controls to the point of intersection would also be altered. Obviously, in lieu of the dash pot relays referred to, any other suitable mechanism might be employed and as afore brought out, the system might be altered according to the particular needs of the

installation without departing from the spirit of the invention as defined by the claims.

Having described my invention, what I claim as new and desire to secure by Letters Patent, is:

- 5 1. A traffic control system including signalling means to be disposed adjacent the intersection of two vehicle lanes and to accord and interrupt right of way to vehicles moving over said lanes, control means connected to said signalling means to cause such operation thereof and a pair of spaced vehicle-responsive controls disposed in one lane to one side and in advance of said intersection, said vehicle-responsive controls being connected to said control means and adapted to 10 be sequentially operated by a vehicle approaching the intersection over such lane and means forming a part of said control means whereby operation of the first vehicle-responsive control causes transfer of right of way indication to the lane in which said controls are disposed and maintains said right of way indication for a period of time, and actuation of the second vehicle responsive control causing said control means to 15 lengthen such period of right of way indication.
- 20 2. A traffic control system including, in combination, signalling means to be disposed at the intersection of a plurality of traffic lanes and to alternately accord and interrupt right of way to traffic moving over said lanes and through said intersection, timing means controlling the operation of said signalling means, a traffic responsive control disposed in one of said lanes and connected to said timing means to accord when actuated through said signalling means right of way to said lane for a minimum period, said traffic responsive control being located at a point relatively remote from the intersection and a further traffic responsive control connected to said timer to extend when actuated the right of way period of such lane, said further control being disposed at a point relatively close to the intersection.
- 25 3. A traffic control system including, in combination, signalling means to be disposed at the intersection of a plurality of traffic lanes and to alternately accord and interrupt right of way to traffic moving over said lanes and through said intersection, timing means controlling the operation of said signalling means, a traffic responsive control disposed in one of said lanes and connected to said timing means to accord when actuated through said signalling means right of way to said lane for a minimum period, said traffic responsive control being located at a point relatively remote from the intersection and a further traffic responsive control connected to said timer to extend when actuated the right of way period of such lane, said further control being disposed at a point relatively close to the intersection, and means forming a part of said timing means for terminating the right of way period of said lane.
- 40 4. A traffic control system including, in combination, signalling means to be disposed at the intersection of a plurality of traffic lanes and to alternately accord and interrupt right of way to traffic moving over said lanes and through said intersection, timing means controlling the operation of said signalling means, a traffic actuated control disposed in one of said lanes at a point relatively remote from the intersection and connected to said timing means to accord when actuated through said signalling means right of way to said lane for a minimum period, means forming a part of said timing means to automatically

transfer through said signalling means the right of way from said lane to another lane upon the expiration of said minimum period, and a further traffic actuated control connected to said timer to prevent, upon actuation, the automatic transfer at the end of the said period, and to extend the right of way period of such first named lane beyond the said minimum period, said further control being disposed at a point relatively close to the intersection.

5 5. A traffic control system including, in combination, signalling means to be disposed at the intersection of a plurality of traffic lanes and to alternately accord and interrupt right of way to traffic moving over said lanes and through said intersection, timing means controlling the operation of said signalling means, a traffic responsive control disposed in one of said lanes and connected to said timing means to accord when actuated through said signalling means right of way to said lane for a minimum period, means forming a part of said timing means to automatically transfer through said signalling means the right of way from said lane to another lane upon the expiration of said minimum period, further means forming a part of said timing means to maintain the transferred right of way in favor of said second lane for a determined period, the traffic responsive control of said first named lane being located at a point relatively remote from the intersection and a further traffic responsive control connected to said timer to prevent, upon actuation, the automatic transfer of right-of-way at the end of such minimum period, and to extend the period of such first named lane, said further control being disposed at a point relatively close to the intersection.

6 6. A traffic control system including, in combination, signalling means to be disposed at the intersection of a plurality of traffic lanes and to alternately accord and interrupt right-of-way to traffic moving over said lanes and through said intersection, timing means controlling the operation of said signalling means, a traffic actuated control disposed in one of said lanes at a point relatively remote from the intersection and connected to said timing means to accord, when actuated, through the signalling means, right of way to said lane for a minimum period, means forming a part of said timing means to automatically transfer through said signalling means the right-of-way from said lane to another lane upon the expiration of said minimum period, and a further traffic actuated control connected to said timer to prevent, upon actuation, the automatic transfer at the end of the said period, and to extend the right-of-way period of such first named lane beyond the said minimum period, said further control being disposed at a point relatively close to the intersection, and means forming a part of said timer to prevent continued extension of right-of-way to such first named lane beyond a predetermined period.

7 7. A traffic control system including, in combination, signalling means to be disposed at the intersection of a plurality of traffic lanes and to alternately accord and interrupt right-of-way to said lanes, timing means controlling the operation of said signalling means, a plurality of vehicle responsive controls disposed in one lane to one side and in advance of said intersection, one of said controls being located relatively remote from the intersection and connected to said timing means so that when actuated while right-of-way is not accorded to the lane of said control

it causes the signalling means through said timing means to shift right-of-way indication to such lane for a minimum period, said timing means functioning in response to control actuation while right-of-way is accorded to said lane to extend the period of right-of-way thereof, the vehicle responsive controls being so spaced that the more distant control extends, upon actua-

tion, the right-of-way period for at least an interval sufficient to permit passage of a vehicle to a control nearer the intersection and the control nearest the intersection, upon actuation extends through said timing means the right-of-way period for a further interval sufficient to allow passage of the vehicle across the intersection.

CHARLES D. GEER.
